UNITED STATES PATENT OFFICE.

JOSEPH M. McGINNIS, OF PHILADELPHIA, PENNSYLVANIA.

REMOVAL VALVE MECHANISM FOR UNDERGROUND LIQUID TANKS.

Application filed January 24, 1924. Serial No. 688,257.

To all whom it may concern:

Be it known that I, JOSEPH M. McGINNIS, a citizen of the United States, and a resident of the city of Philadelphia, county of Philadelphia, State of Pennsylvania, have invented certain new and useful Improvements in Removal Valve Mechanism for Underground Liquid Tanks, of which the following is a specification.

- 10 The present invention relates to underground liquid storage tanks, such for example as gasoline or oil tanks from which the contents are pumped to a point of use. Some of the objects of the invention are to
15 provide a removable valve structure for underground liquid storage tanks; to provide a valve structure arranged to prevent short liquid measure during the pumping operations; to provide valve means for storage tanks to prevent leakage and waste of the liquid; to provide means whereby the check valve of an underground storage tank is accessible for repairs and replacement without requiring excavation; to provide
25 means accessible from the ground level for making repairs to a foot valve of a buried storage tank; to provide means for eliminating the expense and loss of time now required for gaining access to the valves of
30 tanks located below the level of the ground; and to provide other improvements as will hereinafter appear.

In the accompanying drawings, Fig. 1 represents a sectional elevation of an underground liquid storage tank showing one form of removable control valve embodying the present invention; Fig. 2 represents a section on line 2-2 of Fig. 1; Fig. 3 represents a section on line 3-3 of Fig. 1; and Fig. 4 represents a section on line 4-4 of Fig. 1.

Referring to the drawings, one form of the present invention is shown applied to a storage tank 10, such as employed as a reservoir for gasoline, or any other liquid, and which is located in the ground 11, and generally as in the case of inflammable liquids some ten to twenty feet below the ground level.

For the purpose of removing the stored liquid, a discharge pipe 12 is provided, having on its lower end a foot piece 13, the fluid inlet 14 of which is in close proximity to the bottom of the tank 10 so as to insure an emptying of the tank if desired. Any suitable check valve may be employed to control the inlet 14, and in the present instance

a common form is shown comprising a ground valve 15 having guide wings 16 fitting the interior of the pipe 12. A fixed pin 17 is arranged transversely of the pipe 12 to serve as a stop to limit the opening movement of the valve 15 and prevent its displacement. The check valve 15 opens towards the discharge end of the pipe 12. The upper end of the discharge pipe 12 opens into a chamber 18 which has lateral communication with a conduit 19 leading to the suction end of the pump 20 which is above the ground level. The chamber 18 is formed, in the present instance, by a T fitting 21.

In order to support the discharge pipe 12 in a removable manner, a tubular casing 22 is provided, having its lower end threaded into or otherwise joined to an annular flange 23 on the tank 10, while its upper end is threaded into or otherwise fastened to the bottom of the T fitting 21. This casing 22 encircles the discharge pipe 12 and has its upper end provided with a ring 24 forming a seat 25 of spherical form to receive a head 26 having a face 27 seating in and complementary to the seat 25. The two meeting faces of the head 26 and the ring 24 form a ground joint to prevent leakage from the chamber 18 when the pump is in operation. It will be noted that the discharge pipe 12 is thus suspended from the ring 24, and its weight effectually maintains a sealed joint. Further, in case the casing 22 is not accurately set vertical, the ball-like suspension of the pipe 12 allows the latter to take a vertical position and still maintain a leak proof joint. A bail or handle 30 is secured to the head 26 so that a suitable hook or grappling tool can engage it to remove the pipe 12 for repairs.

The upper end of the T fitting 21 is connected to an extension pipe 31 opening above the ground level and normally closed by a cover plate 32 which is preferably threaded over the end thereof.

In order to eliminate the production of a vacuum in this pipe 31 by the action of the pump 20 and thus cause a variation in the measured quantity of liquid being pumped, the lower end of the pipe 31 is provided with an internal flange 33 which forms a seat for a closure 34. To maintain this closure 34 tight it may be connected as shown by a rigid rod 35 to the cap 32 so that when the latter is screwed

into place it will place the closure 34 under pressure and make a leak proof joint.

Having thus described my invention, I claim:

5. A tank construction comprising in combination an underground tank, a shaft having one end connected to said tank and its other end accessible from the ground level, a branch pipe from said shaft connected to a pumping unit, a discharge pipe in said shaft, a control valve in said tank and carried by said discharge pipe, means for removably supporting said discharge pipe from said shaft, a cover for said shaft, and means accessible by removing said cover for withdrawing said discharge pipe and said valve from said shaft.

20. A tank construction comprising in combination an underground tank, a shaft having one end connected to said tank and its other end accessible from the ground level, a branch pipe from said shaft connected to a pumping unit, a discharge pipe in said shaft, a control valve in said tank and carried by said discharge pipe, means for removably supporting said discharge pipe from said shaft, a cover for said shaft, means for sealing the upper end of said shaft from communication with said 30 branch pipe, and means accessible by removing said cover for withdrawing said discharge pipe and said valve from said shaft.

35. A tank construction comprising in combination an underground tank, a shaft having one end connected to said tank and its other end accessible from the ground level, a branch pipe from said shaft connected to a pumping unit, a discharge pipe in said shaft, a control valve in said tank and carried by said discharge pipe, means for removably supporting said discharge pipe from said shaft, a cover for said shaft, means controlled by said cover for sealing the upper end of said shaft from communication with said branch pipe, and means accessible by removing said cover for withdrawing said discharge pipe and said valve from said shaft.

50. 4. A tank construction comprising in combination an underground tank, a shaft having one end connected to said tank and its other end accessible from the ground level, a branch pipe from said shaft connected to a pumping unit, a discharge pipe in said shaft, a control valve in said tank and carried by said discharge pipe, means for removably supporting said discharge pipe from said shaft, a cover for said shaft, means for preventing errors in the measured quantity of liquid pumped, and means accessible by removing said cover

for withdrawing said discharge pipe and said valve from said shaft.

5. A tank construction comprising in combination an underground tank, a shaft comprising a casing secured to said tank, a T fitting and an extension aligned with said casing and extending above the ground level, a discharge pipe in said casing, a control valve on said pipe and located in said tank, a branch pipe from said shaft leading to a pumping unit, means for removably suspending said discharge pipe from said casing, and means for gaining access to said extension to remove said discharge pipe.

6. A tank construction comprising in combination an underground tank, a shaft comprising a casing secured to said tank, a T fitting and an extension aligned with said casing and extending above the ground level, a discharge pipe in said casing, a control valve on said pipe and located in said tank, a branch pipe from said shaft leading to a pumping unit, means including a leak proof joint for removably suspending said discharge pipe from said casing, and means for gaining access to said extension to remove said discharge pipe.

7. A tank construction comprising in combination an underground tank, a shaft comprising a casing secured to said tank, a T fitting and an extension aligned with said casing and extending above the ground level, a discharge pipe in said casing, a control valve on said pipe and located in said tank, a branch pipe from said shaft leading to a pumping unit, means including a ground spherical joint for suspending said discharge pipe from said casing, a lifting means on said discharge pipe, and a removable cover on said shaft whereby access is had to said lifting means.

8. A tank construction comprising in combination an underground tank, a shaft comprising a casing secured to said tank, a T fitting and an extension aligned with said casing and extending above the ground level, a discharge pipe suspended in said casing, a control valve on said pipe and located in said tank, a branch pipe leading to a pumping unit, a seat on the inner end of said extension, a closure arranged to engage said seat, a cover for the upper end of said extension, and means actuated by said cover for holding said closure to said seat.

Signed at Philadelphia, county of Philadelphia, State of Pennsylvania, this 11th day of January, 1924.

JOSEPH M. McGINNIS.
